(57) **CLAIM**

The ornamental design for a swivel assembly for back-pack mounted equipment, as shown and described.

DESCRIPTION

FIG. 1 is a left side elevational view of my swivel assembly for back-pack mounted equipment, with the swivel plate aligned with the back plate, and wherein the right side elevational view comprises a mirror image thereof;

FIG. 2 is a left end elevational view thereof taken from a position generally to the left of FIG. 1, the right end elevational view comprising a mirror image;

FIG. 3 is a reduced scale top plan view thereof, with the swivel plate aligned with the back plane and in FIGS. 1 and 2;

FIG. 4 is a reduced scale bottom plan view of the back plate with swivel plate omitted for clarity; and,

FIG. 5 is a reduced scale top perspective view thereof, with the swivel plane aligned with the back plate for clarity.
